TREMOLO UNIT FOR A STRINGED MUSICAL INSTRUMENT

James Ormston Burns, Buckhurst Hill, Essex, England,
assignor to Ormston Burns Limited, Buckhurst Hill, England

Filed Dec. 19, 1961, Ser. No. 67,970

Claims priority, application Great Britain June 30, 1961

Term of patent 14 years

(Cl. D56—1)

FIG. 1 is a top plan view of a tremolo unit for a stringed musical instrument, showing my new design;
FIG. 2 is a bottom plan view;

FIG. 3 is a top front perspective view; and
FIG. 4 is a rear elevation view.

I claim:

The ornamental design for a tremolo unit for a stringed musical instrument, substantially as shown.
